UNITED STATES PATENT OFFICE.

S. HODGINS, OF ST. LOUIS, MISSOURI, ASSIGNOR TO HIMSELF AND STEPHEN BLACKIE, OF SAME PLACE.

IMPROVEMENT IN FASTENINGS FOR PAPER COLLARS.

Specification forming part of Letters Patent No. **56,854**, dated July 31, 1866.

To all whom it may concern:

Be it known that I, S. HODGINS, of St. Louis, in the county of St. Louis and State of Missouri, have invented a new and Improved Collar-Fastening; and I do hereby declare that the following is a full, clear, and exact description thereof, which will enable others skilled in the art to make and use the same, reference being had to the accompanying drawings, forming part of this specification, in which—

Figure 1 is a front view of my invention applied to a gentleman's collar. Fig. 2 is a longitudinal section taken on the plane of the line *xx*, Fig. 1. Fig. 3 is a modification of my invention.

Similar letters of reference indicate like parts.

My invention consists in the employment of a piece of rubber or other elastic fabric or material having a button-hole in one end and a metallic hook at its other end, the latter to be hooked into the front of the band of the collar, one for each side, and the button-hole being intended to be placed over the usual button or stud affixed to the neck-band of the shirt.

A A' designate the two sides of a collar, and B the neck-band of a shirt, which I have illustrated to show the application of my invention.

C C' are two pieces of rubber of suitable size. In one end of each piece C a slit is cut, which constitutes a button-hole, and is intended to be placed over the button *a* in the shirt-band for securing the same thereto. The other end of each elastic C carries a metallic plate, D, which has a bifurcated end, the forks or prongs *c* being thrust through the elastic C, and bent down so as to secure the plate thereto, and the other end of the plate D is bent

over so as to form a hook, *d*, which hook is to be thrust through a slot in the band of the collar and pressed down so as to clasp it firmly, as shown clearly in Fig. 2.

In Fig. 3 the elastic is shown as having a plate and hook at each end and a button-hole in the middle. In this case, to use the collar, the one end of the fastening must be taken from the collar in order to remove the collar.

I will here remark that this device will afford much comfort to the wearers of paper collars. In the first place there will be no danger of tearing out the button-holes, which often occurs, even with the cloth-lined collars, when putting them on. In the second place the collar, though of the right size, is often uncomfortable at certain times by reason of the rigid manner in which it encircles the neck. With my invention both these objections are set aside, there being no danger of tearing out the button-holes, and the elastic will give or stretch a little, so as to make the collar set easily and fit the neck snugly without any liability of its chafing the neck.

The fastening can be used for quite a long time. The mode of fastening it to the collar is so quickly performed as to make it desirable on that account, and the comfort they will afford to the neck, for even a single day, recommends them as useful articles.

What I claim as new, and desire to secure by Letters Patent, is—

An elastic strip provided with one or more button-holes and one or more hooks, when arranged in relation to a paper collar substantially as described.

SAMUEL HODGINS.
